W. S. MACLEWEE,

FUSE PLUG.

APPLICATION FILED OCT. 25, 1918.

Patented Mar. 28, 1922.

FIG. 1.

FIG. 2.

FIG. 3.

FIG. 4.

Inventor:

William S. MacLewee

By his Attorney

F. Hellitt Goodwin

UNITED STATES PATENT OFFICE.

WILLIAM S. MACLEWEE, OF TRENTON, NEW JERSEY, ASSIGNOR TO CARRIE HOWELL
MACLEWEE, OF TRENTON, NEW JERSEY.

FUSE PLUG.

1,410,695.

Specification of Letters Patent. Patented Mar. 23, 1922.

Application filed October 25, 1918. Serial No. 259,645.

To all whom it may concern:

Be it known that I, WILLIAM S. MACLEWEE, a citizen of the United States, residing at Trenton, in the county of Mercer and State of New Jersey, have invented certain new and useful Improvements in a Fuse Plug, of which the following is a specification.

My invention relates to improvements in fuse plugs and particularly relates to improvements in a fuse plug for which Letters Patent No. 1,243,851 of the United States were granted to me on the 23rd of October, 1917.

The object of the present invention is to provide means for securing the ends of the strip of fuse metal at the points of contact with the fuse plug without the use of solder; a further object of my invention is to provide the post for supporting the metal strip, to which one end of the fuse member is attached, with means on the end thereof for preventing the said metal strip from slipping off the end of the post and a still further object of my invention is to provide a novel form of attaching the fuse member to the central contact button. These together with various novel features of construction and arrangements of the parts, which will be fully hereinafter described and claimed, constitute my invention.

Referring to the drawings:

Fig. 1, is a vertical section of my improved fuse plug, drawn on a scale which is double the actual size; Fig. 2, is a perspective view of the inner insulating disk having a supporting post forming part thereof; Fig. 3, is a sectional perspective view of the metal shell and metal contact plate forming part thereof; and Fig. 4, is a plan view of the disk of insulating material forming the end of the fuse plug.

In the drawing in which like reference characters refer to like parts, 1 represents the metal shell adapted to be secured to a body portion 2 of insulating material, which body portion may be of any standard form. The metal shell 1 is provided with a screw thread for inserting the plug into a socket, in the usual manner, and thereby complete an electric circuit through the fuse member 4 of the fuse plug.

The metal shell 1 is provided with a contact plate 5, forming part of the inwardly turned flange 6, and said contact plate 5 is

provided at its inner end with an enlarged head 8, having an elongated opening 9 formed therein for the insertion of one end of the flat strip of fuse metal 4. The fuse member 4 is of soft pliable metal and may be tightly clamped around the cross bar or end portion 10, of the metal plate 5, as shown in Fig. 1, and thus forms a good electrical contact without soldering the parts together. The particular advantage of this form of attachment for the fuse member is, that the necessity of clamping the contact plate 5, around the fuse member, is avoided. The metal strip 5 being made of hard metal will break if bent sharply or clamped over upon itself and for this reason it has heretofore been considered necessary to solder such connections.

By passing the end of the fuse strip 4 through the narrow slot 9, formed in the head of the plate 5, the parts cannot become disconnected. Should the fuse strip 4 become loose on the cross bar 10, the fuse strip could only move on the cross bar a distance equal to the width of said slot 9 and the fuse strip would have to be unfolded to the extent of a right angle before the end could jump out of the slot in the plate 5 and become disconnected.

The contact plate 5 is stamped from the portion of the blank forming the bottom of the shell 1 and is made as long as the amount of metal in the blank will permit, so that when said plate 5 is bent inwardly it will have sufficient length to extend beyond the cylindrical edge of the shell 1, thus making the end accessible for conveniently attaching the fuse member 4.

Two disks 12 and 14 of insulating material are secured by the central contact button or rivet 16. Said disks engage the flange 6 of the shell 1 between them and form a complete unit which may be attached to any body portion.

The inner disk 12 is made of fiber and provided with a tongue which forms a post 18 to support the contact plate 5. The free end of the post 18 is recessed to form lugs 19 and 20 and the contact plate 5 is bent over upon the top of the post and rests between said lugs which hold the contact plate from slipping off the end of the post.

The disks 12 and 14 are each provided with an aperture 13 and 15, through which the opposite end of the fuse member 4 is passed.

- The fuse member is then bent over and the end is inserted into the central apertures 22 and 23 formed in the disks to receive the cylindrical portion of the contact button 16.
- 5 The inner surface of the head 17 of the contact button 16 rests upon and makes a good contact with the fuse strip 4, when the inner end of the contact button is riveted upon the said disks. By passing the end of the fuse member through both disks it is brought into contact with the head of the button and should the latter become loose a good contact will still be made when pressure is brought against the head of the button, by the screwing 10 of the shell into a socket which will cause the disk 14 to press the fuse member tightly against the under side of the head of the button.
- 15 Having thus described my invention I claim and desire to secure by Letters Patent:

1. A fuse plug comprising a metal shell adapted to be secured to a body portion, a contact plate extending from the metal shell

into the interior thereof, a central contact button, a fuse member connecting the said contact plate with said button, a disk carrying said central contact button, said disk having a tongue formed thereon and extending into the interior of the metal shell and forming a post to support the said contact plate, and means formed upon the end of said post to hold the contact plate thereon.

2. A fuse plug comprising a metal shell adapted to be secured to a body portion, a contact plate extending from the metal shell 35 into the interior thereof, a central contact button, a fuse member connecting the said contact plate with said button, a disk carrying said contact button, said disk having a post formed thereon for supporting said contact plate and lugs formed upon the end of said post adapted to hold the contact plate upon the post.

In testimony whereof I affix my signature.

WILLIAM S. MacLEWEE.
